HECTOGRAPHIC AND LIKE DUPLICATING MACHINES

Leslie Ernest Brougham, Hammersmith, London, England, assignor to Block & Anderson Limited, London, England, a British company.

Filed Feb. 26, 1960, Ser. No. 11,209

Claims priority, application Great Britain Mar. 2, 1959
3 Claims. (Cl. 101—132.5)

This invention relates to hectographic and like duplicating machines and is more particularly concerned with a duplicating machine comprising a master-carrying printing drum which is rotatable manually by a crank handle.

In machines of such type it is necessary to provide means for ensuring the arrest of the printing drum at a predetermined initial or starting position in order to permit the accurate feeding-in of the copy sheet with relation to the image on the master sheet which is supported by the printing drum. In order to do so it is customary to provide some form of locating means, such as a spring-urged roller carried upon the machine frame and adapted to enter a depression or dwell region in the contoured surface of a cam disc carried by the printing drum. When such drum is arranged for rotation by the manual crank handle through a speed reducing gear train, for instance one affording a 2:1 speed reduction whereby two complete revolutions of the crank handle are needed to rotate the drum through each operative single-revolution printing cycle, the provision of the requisite degree of accuracy of location in the required starting position without, at the same time, imposing an excessive resistance to resumed movement of the crank handle away from such locating position in order to effect the next operation, is not unduly difficult. When, however, for simplicity and cheapness it is desired to eliminate the speed reduction gearing and to couple the crank handle directly to the printing drum, the provision of an adequate degree of accuracy of positioning of the drum without excessive resistance to resumed movement of the crank handle may become difficult.

This difficulty is increased when the machine is arranged to employ damping or moistening means of the pad type for applying a film of solvent liquid to the surface of the copy sheet as it enters the printing bight or nip between the printing drum and a co-operating counter-pressure roller. The reason for this is that, with such pad type damping means, it is essential also to lift or otherwise separate the damping pad from an opposing copy sheet supporting surface at the same initial or starting position in order to permit free passage of the forward edge of the new copy sheet then being presented to the machine past such damping pad and right up to the printing nip. This positioning of the new copy sheet is essential in order that the sheet may be gripped within such nip immediately the printing drum commences its next rotation and is thereby drawn into the machine in proper registration with the master image carried by the printing drum. At the same instant, the damping pad must be lowered again on to the copy sheet in order to ensure that the commencement of the moistened region of such sheet arrives at the printing nip before the first part of the master image.

Such pad lifting movement and the subsequent pad lowering movement on to the copy sheet immediately the latter starts to move forwardly must be effected automatically and are usually brought about by means of a further cam secured to the printing drum and operating through a suitable rise or projection thereon to control lever mechanism which is coupled to the damping pad whereby the latter is moved away from its normal sheet contacting position against the action of biasing spring

2

means as the printing drum is brought to the said initial or starting position.

So far as the operator is concerned, the effect of such pad lifting arrangements is to make the precise starting position more difficult to determine since it now occurs intermediate a first position of the crank handle where extra pressure is needed to cause the lifting of the damping pad and a second position where the operating pressure required is temporarily lessened as the damping pad returns again to its lowered operative position under the influence of its biasing spring. The result is a tendency for the operator to overshoot the required starting position unless the resistance to movement imposed by the aforesaid locating means is still further increased.

15 An object of the present invention is to provide an improved and simplified construction for use in such machines having a direct or 1:1 driving connection between the operating crank handle and the printing drum whereby the above described difficulty of drum location is reduced or eliminated.

20 In an arrangement according to the invention the operating crank handle is provided with a stop member positioned normally to engage with a stationary abutment carried upon the machine frame in a position which positively arrests the printing drum in the required starting position, such stop member being itself movable manually, as by pressure of the thumb or finger of the operator while grasping the crank handle, against the action of spring biasing means to a position where such stop is moved 25 clear of said stationary abutment thereby to permit the commencement of a fresh operative stroke of the crank handle. Preferably, the manually engageable part of 30 said movable stop member is so positioned relatively to the handle grip of the crank handle, that it must be released by the operator as the crank handle is rotated forwardly through a complete operative revolution.

35 In order that the nature of the invention may be more readily understood one particular constructional embodiment thereof will now be described by way of illustrative example with reference to the accompanying drawings in 40 which:

FIG. 1 is a plan view of an operating crank handle arrangement in accordance with the invention.

FIG. 2 is a corresponding side elevational view of the 45 arrangement of FIG. 1.

FIG. 3 is a vertical cross-section taken through a spirit duplicating machine embodying known forms of drum locating and damping pad lifting arrangements while

50 FIG. 4 is a side elevational view of a machine similar to that shown in FIG. 3 but incorporating the drum locating arrangements of the present invention.

55 Reference will first be made to FIG. 3 in which the machine shown comprises a printing drum 21 secured to a horizontal axle 22 journaled at each end in the side frame plates 20 of the machine and of which only the left-hand plate is shown. The drum 21 has an operating crank handle 10 directly connected thereto and is provided with an axially directed slot 23 in its peripheral surface for receiving and holding, in already known manner, a leading edge of the image-bearing master sheet 24 which is normally disposed wrapped around a part 60 of the peripheral surface of the drum. The drum 21 co-operates with a counterpressure roller 25 secured upon a spindle 26 which is conventionally mounted in spring-urged support means (not shown) whereby such counterpressure roller is urged resiliently towards the printing drum with a pressure which can be adjusted at will by the operator. Each copy sheet, as shown at 27, is fed to the printing bight or nip 28 between the drum and counterpressure roller over a feed plate 29 extending 65 between the side frame plates 20. After passing

through the printing nip the printed copy sheet is delivered over a delivery plate 30.

To effect damping or moistening of each copy sheet as it passes into the printing nip, there is provided pad-type damping mechanism 31 including a pad 32 of felt or like material carried in a box-like casing 33 provided with a liquid supply conduit 34. The pad 32 with its casing 33 is carried, in readily removable manner, in a guide channel formed between plates 35 and 36 forming part of a support structure 37 which is pivotally mounted at each side and as indicated at 38 upon the opposite side plates 20. Attached to such support structure 37 is an arm 38 carrying a cam follower roller 39 at its free end. Such follower roller is biased, as by spring means 40, towards the periphery of a cam disc 41 secured to the drum 21. The cam disc 41 has a single raised portion 42 and the arrangement is such that, only when such raised portion is under the cam follower roller 39, is the damping pad 32 lifted clear of the feed plate 29 thereby to allow unobstructed feeding-in movement of the copy sheet 27 right up to the printing bight 28. At all other positions of the cam disc 41, the pad 32 is lowered so as to wipe the upper surface of the copy sheet as it passes to the printing nip 28.

The printing drum 21 is shown in FIG. 3 in the aforementioned initial or starting position and is located in such position by means of a cam follower roller 43 which is carried at the free end of a lever arm 44 pivotally mounted upon the left-hand side plate 20 and is resiliently urged by spring means 45 into a dwell region 46 in the periphery of a further cam disc 47 connected to the printing drum 21.

As will be apparent from FIG. 3, the movement of the printing drum 21 to the initial or starting position, as shown, by means of the crank handle 10, necessitates some increase in the pressure applied to the handle in order to lift the cam follower roller 39 up on to the peak of the raised portion 42 of the cam disc 41. When such roller 39 is resting upon the peak of this raised portion 42, the other cam follower roller 43 has dropped into the dwell region 46 of the cam disc 47 and in so doing has tended to apply a limited amount of forward torque to the drum 21. Similarly when rotation of the crank handle is resumed to commence a fresh operative cycle, the return of the cam follower roller 39 down the opposite side of the raised portion 42 projection tends to assist the operator by lessening the pressure required upon the crank handle but the need to move the cam follower roller 43 out the dwell 46 of the cam disc 47 calls for some additional operating pressure. The two effects to some extent counterbalance one another and as a result it is difficult to provide a positive locating action which can readily be sensed by the operator unless the dwell region 46 is made deep or steep sided or, alternatively, heavy spring pressure is applied by the spring means 45. In view of the direct driving connection between the crank handle 10 and the drum 21 any such measures to increase the sense of positive location in the initial or starting position not only increase the effort required from the operator to start each operation but also tend to introduce erratic or jerky operation of the machine whereby the speed of rotation of the printing drum is uneven. This can result in poor quality prints by reason of inequality of the amount of solvent applied to the copy sheet as it is moved with varying velocity beneath the damping pad 32.

Referring now to FIG. 4, showing one arrangement in accordance with the invention, the drum locating means of FIG. 3, consisting of the cam follower roller 43 and the cam disc 47 are eliminated and instead the crank handle 10 is provided with a movable stop, indicated generally at 14, which is normally biased to a position where a part 15 thereof positively engages a stationary abutment 19 fixed to the outer surface of the right-hand side frame plate 20. When such engagement

takes place the drum 21 is arrested in the desired initial or starting position identical with that shown in FIG. 3.

Referring now also to FIGS. 1 and 2, the crank handle 10 comprises a conventional radial arm 12 carrying an outwardly projecting grip roller 13 at its free end. Adjacent this grip roller 13, on the inside or frame facing surface of the arm 12, is arranged the movable stop member 14 consisting of a metal plate having an in-turned lug 15 at its lower end and an outwardly turned thumb piece 16 at its upper end such thumb piece being positioned to overlie the end of the arm 12 immediately alongside the grip roller 13 when the parts are in the position as shown in FIG. 4, which corresponds to that of the initial or starting position of the drum 21.

The stop member 14 is pivotally mounted upon the arm 12 by means of a pivot arm 18 and is biased by means of a spring 17 disposed around such pivot pin 18 so as normally to occupy the position shown in full lines in FIGS. 1, 2 and 4. In this position the lug 15 is so positioned that it comes into positive engagement with the fixed stop pin 19 projecting outwardly from the adjacent side frame plate 20 of the machine as the crank handle is moved downwardly in the direction of the arrow a, FIG. 2, at the completion of each operative stroke of the handle.

To commence a fresh stroke of the crank handle in order to effect a further printing operation upon the newly inserted copy sheet, the operator must first depress the thumb piece 16 thereby to move the lug 15 clear of the stop pin 19. Such depressed position is shown in chain dotted lines in FIG. 4. The crank handle 10 can now be rotated but, by reason of the position of the thumb piece 16 with relation to the free end of the crank handle, this thumb piece must automatically pass from under the thumb of the operator as the crank handle is rotated first downwardly and then upwardly again through a complete revolution since at a position 180° displaced from that shown in FIG. 4, the thumb piece 16 is lying underneath and not on top of the crank handle. In consequence as the crank handle again approaches the position shown in FIG. 4 from above, the released stop member 14 is in a position where the lug 15 again engages the stop pin 19 and so arrests the drum 21 in the correct initial position at the precise end of one operative revolution of the drum.

The arrest position of the crank handle 10 is preferably arranged, as shown, to be approximately 90° beyond its uppermost vertical position whereby the initial starting movement of the crank handle is always downwards towards the table or other surface by which the machine is supported. This avoids any tendency for a machine which is of relatively light construction to be lifted by the applied manual operating pressure.

In certain forms of machine, particularly portable machines, it is desirable that the crank handle shall be readily detachable. In the particular embodiment shown this requirement is met by providing the centre boss of the handle with a projecting spigot pin 11 having a flat surface 48 at its free end for co-operation with a complementary D-section region of an axial bore in the drum axle 22 in order to set up the requisite driving connection between the drum 21 and the handle 10.

I claim:

1. A hectographic duplicating machine comprising a machine framework and a printing drum rotatably mounted therein, a manually operable crank handle operatively connected to said printing drum by a 1:1 driving connection, a stop member comprising a metal plate having an outwardly bent thumb receiving portion at one end and an inwardly bent stop-forming lug at its opposite end, said stop member being pivotally mounted on the inner surface of said crank handle for rocking movement about a point intermediate said inwardly and outwardly bent portions, spring means biasing said stop member to a first position, and a stationary abutment on said ma-

chine framework positioned to be in the path of said stop-forming lug when said stop member is in said first position to arrest said drum in the correct position for commencement of an operation cycle of the machine, said stop member being movable against said spring means by pressure applied to said thumb-receiving portion to a second position where said stop-forming lug is clear of said stationary abutment to allow commencement of said operation cycle.

2. A hectographic duplicating machine comprising a machine framework and a printing drum rotatably mounted therein, a manually operable crank handle including a handle grip directly connected to said printing drum, a stop member comprising a metal plate having an outwardly bent thumb receiving portion at one end and an inwardly bent stop-forming lug at its opposite end, said stop member being pivotally mounted at the free end of said crank handle with said thumb-receiving portion overlying said handle grip for rocking movement about a point intermediate said inwardly and outwardly bent portions, spring means biasing said stop member to a first position, and a stationary abutment on said machine framework positioned to be in the path of said stop-forming lug when said stop member is in said first position to arrest said drum in the correct position for commencement of an operation cycle of the machine, said stop member being movable against said spring means by pressure applied to said thumb-receiving portion to a second position where said stop-forming lug is clear of said stationary abutment to allow commencement of said operation cycle.

3. A hectographic duplicating machine comprising a machine framework and a printing drum rotatably mounted therein, a manually operable crank handle provided with a spigot having a flattened free end, a complementary socket for said spigot end in said drum to provide a readily releasable direct driving connection between said handle and said printing drum, a stop member comprising a metal plate having an outwardly bent thumb receiving portion at one end and an inwardly bent stop-forming lug at its opposite end, said stop member being pivotally mounted on the inner surface of said crank handle for rocking movement about a point intermediate said inwardly and outwardly bent portions, spring means biasing said stop member to a first position, and a stationary abutment on said machine framework positioned to be in the path of said stop-forming lug when said stop member is in said first position to arrest said drum in the correct position for commencement of an operation cycle of the machine, said stop member being movable against said spring means by pressure applied to said thumb-receiving portion to a second position where said stop-forming lug is clear of said stationary abutment to allow commencement of said operation cycle.
